(57) **CLAIM**

The ornamental design for a vessel with lid as shown and described.

DESCRIPTION

FIG. 1 is a perspective view of a vessel with lid;

FIG. 2 is a top plan view thereof;

FIG. 3 is a front elevation view thereof;

FIG. 4 is a left side elevation view thereof;

FIG. 5 is a rear elevation view thereof;

FIG. 6 is a right side elevation view thereof;

FIG. 7 is a bottom plan view thereof;

FIG. 8 is a perspective view thereof, with the lid shown separately for ease of illustration;

FIG. 9 is a top plan view of FIG. 8;

FIG. 10 is a front elevation view of FIG. 8;

FIG. 11 is a left side elevation view of FIG. 8;

FIG. 12 is a rear elevation view of FIG. 8;

FIG. 13 is a right side elevation view of FIG. 8;

FIG. 14 is a bottom plan view of FIG. 8;

FIG. 15 is a perspective view of FIG. 1, with the vessel shown separately for ease of illustration;

FIG. 16 is a top plan view of FIG. 15;

FIG. 17 is a bottom plan view of FIG. 15; and,

FIG. 18 is a front elevation view of FIG. 15—the left side, the right side, and the rear elevation views being identical to the front elevation view.

The broken lines shown in the drawing views show portions of the vessel with lid that form no part of the claimed design. The jagged broken lines with brackets are symbolic breakaways, and any portions of the vessel with lid between the breakaways form no part of the claimed design.
